Patented Feb. 4, 1958

182,053

COMBINATION FLASHLIGHT AND MAGNIFYING GLASS OR SIMILAR ARTICLE

Louise S. Weston and Lois S. Miner, Tucson, Ariz.

Application April 17, 1957, Serial No. 45,763

Term of patent 14 years

(Cl. D48—24)

Fig. 1

Fig. 2

Fig. 3

Figure 1 is a top plan view of the combination flashlight and magnifying glass or similar article embodying our new design;

Figure 2 is a side elevational view thereof;

Figure 3 is a front view thereof.

The rear and side not shown are substantially plain.

This application is a continuation-in-part of our previous application, Serial No. D. 40,451 filed March 5, 1956, now abandoned.

We claim:

The ornamental design for a combination flashlight and magnifying glass or similar article, as shown and described.
